UNITED STATES PATENT OFFICE.

OTTO F. FOGELSTRAND, OF KENSINGTON, CONNECTICUT, ASSIGNOR TO HART MANUFACTURING COMPANY, OF SAME PLACE.

DESIGN FOR FIRE-DOG OR ANDIRON.

Specification forming part of Design No. **6,142**, dated September 17, 1872.

To all whom it may concern:

Be it known that I, OTTO F. FOGELSTRAND, of Kensington, in the county of Hartford and State of Connecticut, have invented a Design for a Fire-Dog or Andiron, of which the following is a specification:

The nature of my design is fully represented in the accompanying engraving, to which reference is made.

A represents the upright, and B the horizontal arm or dog. The edges of the arm B are corrugated or waved, as shown, and the sides of said arm and its rear foot are bordered by a ledge. At the rear end of the arm B, and at a short distance from the upright, are

scroll-like projections α α . The contour of the upright A is composed of straight and curved lines in the form shown, and several openings are formed in the body of said upright, the front surface of which is finished in raised ornaments.

I claim as my invention—

1. The design for the upright A, as shown in the drawing.
2. The design for the arm B, as shown in the drawing.

OTTO F. FOGELSTRAND.
